UNITED STATES PATENT OFFICE.

JAMES D. FRARY, OF NEW BRITAIN, CONNECTICUT, ASSIGNOR TO
LANDERS, FRARY & CLARK, OF SAME PLACE.

DESIGN FOR A LABEL.

Specification forming part of Design No. 7,517, dated June 30, 1874; application filed June 17, 1874.
[Term of Patent 14 years.]

CASE B.

To all whom it may concern:

Be it known that I, JAMES D. FRARY, of New Britain, in the county of Hartford and State of Connecticut, have invented a new Design for a Label; and I do hereby declare the following, when taken in connection with the accompanying illustration, to be a full, clear, and exact description of the same, and which said illustration constitutes part of this specification and represents one of the labels.

This invention relates to a design for label to be placed upon a package or case of table-cutlery; and consists in the peculiar form of ornamented border, as hereinafter described, and shown in the accompanying illustration, which incloses the descriptive portion of the label and illustrations; also, in the arrangement of the filling in, as shown and described.

The outline of the border is a rectangle, the angles indented and filled with an angle ornament. The space within the border is divided into an upper and lower panel by an or-

nament of scroll-work from each side running inward, and dying out near the center. The lower panel contains a description of the contents of the package; the prominent words "Table Cutlery," in a straight line across the panel; the maker's name below in an inverted segmental line; at the top of the upper panel the make or quality in a segment over a vignette; beneath which is the maker's name in a serpentine line across the label, and below a second vignette.

The four lines of letter-press described with two vignettes of some character, constitute the essential feature of the second part of this design.

I claim as my invention—

The design for label, as shown in the accompanying illustration, and herein described.

JAS. D. FRARY.
